US00D840691S

(12) **United States Design Patent** (10) Patent No.: **US D840,691 S**
 (45) Date of Patent: **** Feb. 19, 2019**

(54) **ORAL CARE IMPLEMENT**

- (71) Applicant: **Colgate-Palmolive Company**, New York, NY (US)
- (72) Inventors: **Wen Jin Xi**, Shanghai (CN); **Robert Moskovich**, East Brunswick, NJ (US); **Guang Sheng Guo**, Yangzhou (CN); **Stephen Nelson**, New Brunswick, NJ (US); **Joachim Storz**, Zell am See (AT); **Felix Mueller**, Weil der Stadt (DE)
- (73) Assignee: **Colgate-Palmolive Company**, New York, NY (US)

(**) Term: **15 Years**(21) Appl. No.: **29/586,629**(22) Filed: **Dec. 6, 2016****Related U.S. Application Data**

- (62) Division of application No. 29/533,922, filed on Jul. 23, 2015, now Pat. No. Des. 777,446.
- (51) **LOC (11) Cl.** **04-02**
 (52) **U.S. Cl.** **D4/104**
- (58) **Field of Classification Search**

(57) **CLAIM**

The ornamental design for an oral care implement, as shown and described.

DESCRIPTION

FIG. 1 is a front right perspective view of an oral care implement;

FIG. 2 is a rear left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines depict portions of the article that form no part of the claimed design.

1 Claim, 4 Drawing Sheets
